(57) CLAIM

The ornamental design for a cartridge holder, as shown and described.

DESCRIPTION

FIG. 1 is a perspective view of the new cartridge holder design with its lid in a fully closed position;

FIG. 2 is a perspective view of the new cartridge holder design with its lid in a fully open position to reveal its bullet chambers.

FIG. 3 is a front view of the cartridge holder;

FIG. 4 is a rear view of the cartridge holder;

FIG. 5 is a side view of the cartridge holder;

FIG. 6 is a side view of the cartridge holder;

FIG. 7 is a bottom end view of the cartridge holder;

FIG. 8 is a top end view of the cartridge holder; and,

FIG. 9 is a perspective view of the cartridge holder shown with its lid in a partially open position.

The broken lines are for illustrative purposes only and form no part of the claimed design.

The cartridge holder is shown broken away for ease of illustration and to indicate indeterminate length.
